United States Patent Office.

GARRETTSON SMITH AND HENRY BROWN, OF PHILADELPHIA, PENNSYLVANIA, ASSIGNEES TO C. S. FRANCIS, HENRY FRANCIS, H. L. BUCKWALTER, J. A. BUCKWALTER, AND JOHN SHEELER.

Design No. 4,171, dated June 21, 1870.

DESIGN FOR A COOKING-STOVE.

The Schedule referred to in these Letters Patent and making part of the same.

To all whom it may concern:

Be it known that we, GARRETTSON SMITH and HENRY BROWN, both of the city of Philadelphia, in the State of Pennsylvania, have invented and produced a new and original Design for a Cooking-Stove, of which the following is a specification.

The nature of our design is fully represented in the accompanying drawing, which forms a part of this specification.

What we claim as our invention, and desire to secure by Letters Patent of the United States, is—

The design for a cooking-stove, as shown.

GARRETTSON SMITH.
HENRY BROWN.
